M. W. LONG, OF BANGOR, MAINE.

Letters Patent No. 80,751, dated August 4, 1868.

IMPROVEMENT IN STOVE-OVENs.

The Schedule referred to in these Letters Patent and making part of the same.

TO ALL WHOM IT MAY CONCERN:

Be it known that I, M. W. LONG, of Bangor, in the county of Penobscot, and State of Maine, have invented a new and useful Improvement in Stove-Ovens; and I do hereby declare that the following is a full, clear, and exact description of the construction and operation of the same, reference being had to the accompanying drawings, making a part of this specification, in which—

Figure 1 is a top or plan view, and

Figure 2 is a side elevation, with a part of the floor of the oven and side walls of the flue broken away, to show the interior arrangement.

The nature of my invention consists in forming the bottom or floor of stove-ovens with a circular opening, in which is fitted a disk bearing upon ledges, this disk being arranged to revolve for the purpose of changing the position of articles being cooked in the oven; also, in a circular line of small cogs formed upon or attached to the under side of the disk, this rack or circle of cogs fitting into a pinion upon a shaft extending from the outside into the flue under the oven, and having a crank attached to the outer end for the purpose of actuating the pinion and thereby rotating the disk; and also in a grate, which is rotated with the disk, and which is formed with suitable pivots or points upon the under side, which points fit into recesses in the revolving disk, and allow the grate to bear upon it when desired, and when it is desired to raise the grate, it is revolved relatively to the disk, when the points travel up inclined planes formed in the disk, and thereby raise the grate.

Similar letters of reference indicate corresponding parts in the several figures.

To enable others skilled in the art to make and use my invention, I will proceed to describe its construction and operation.

In the drawings, A represents the bottom or floor of the oven, and a is the circular disk, which is fitted into the floor, and bears upon ledges, as is plainly shown in fig. 2.

b is the rack or circular line of cogs, which are formed upon the under side of disk a.

c is the pinion, which meshes into rack b. This pinion is secured upon shaft m, as is also crank d, by which the pinion is rotated. The shaft m passes through the side of the stove, so that the crank is outside while the pinion is inside, the flue B, which is the heated-air passage beneath the oven, being enclosed by the floor A, bottom C, and the usual side and end walls.

f is the grate, which is about the size of disk a; and which is here shown formed with a circular rim and parallel bars across it. Upon the under side of this grate are formed projections or pins at suitable distances around the rim, as shown at k k, and also, if desired, near the centre. These points fit into recesses of suitable depth in the disk, these recesses being formed upon a curve corresponding to that described by the points when the grate is rotated, and being also formed vertical at one end, with an ascending incline to the surface as shown at i.

This grate and the disk a may be so arranged that the top of the grate, when lowered, will be flush with the top of the floor of the oven, or the grate may rise its thickness, as shown.

By thus having the grate adjustable, if the heat be too great, then, by slightly revolving the grate so that the pins k travel up the inclines in the disk, the grate is raised so as to allow an air-passage beneath it, and the effect of the heat is diminished.

The removable handle I, which fits into seats in the grate, furnishes a ready means of rotating it. By forming the oven-floor with a revolving disk, it furnishes a ready means of cleansing the lower flues, and not only can the positions of the various dishes be changed relatively to the fire-box, but if only one dish be cooking, it may be readily rotated so as to present either side to the greatest heat, and this is accomplished without disturbance of the dishes which are being cooked, and without the labor and trouble usually attendant upon such operation.

The disk a may be rotated by a great variety of means, and it may be arranged to move either upon friction-rollers or other bearings, if necessary, in any case, and shaft m may pass through the stove, and be provided with a crank at each end, so that the disk may be revolved from either side of the stove.

g is a centre pivot formed upon the grate, and which passes down through the disk, holding the grate in position. This pivot may be provided with a screw-nut, or its equivalent, affording the means of raising the disk when necessary.

Having thus described my invention, what I claim as new, and desire to secure by Letters Patent, is—

1. The grate *f*, when constructed and operated substantially in the manner specified.
2. In combination with the grate *f*, the disk *a*, fitted to revolve in the manner and for the purpose substantially as shown and described.
3. The device for raising the grate, consisting of pins *k*, upon the under side of the grate, and the inclines *i* in the disk, whereby the grate is raised or lowered at will, by revolving it relatively to the disk, substantially as and for the purposes specified.
